UNITED STATES PATENT OFFICE.

AUGUST C. CHRISTENSEN, OF BROOKLYN, NEW YORK.

GAS AND STEAM PISTON METER.

SPECIFICATION forming part of Letters Patent No. 340,763, dated April 27, 1886.

Application filed January 21, 1886. Serial No. 189,240. (No model.)

To all whom it may concern:

Be it known that I, AUGUST C. CHRISTENSEN, of Brooklyn, county of Kings, and State of New York, have invented certain new and useful Improvements in Gas and Steam Meters, of which the following is a specification.

This invention relates to certain improvements in the water and steam meter for which Letters Patent were granted to me heretofore, No. 269,260, dated December 19, 1882, which improvements are designed with a view to adapt the meter for measuring gas, and especially natural gas, and to reduce the expense of the meter, so as to adapt it for the purpose mentioned.

The invention consists of an inclosing-easing, the bottom-part of which has, in place of the cross-passages at the bottom of the casing, vertical passages and cross-pipes connecting said passages and devices by which the pipes are applied detachably to the bottom of the casing.

The invention consists, further, of an inclosing-easing having a valve-chest, cylinders, and intermediate guides, combined with reciprocating pistons, gridiron slide-valves, screws connecting the slide-valves with the pistons, and helical springs interposed between the slide-valves and the heads of the screws, as will more fully appear hereinafter, and finally be pointed out in the claims.

In the accompanying drawings, Figure 1 represents a plan of my improved gas and steam meter in which the top plate and counter are removed, so as to show the admission valves. Fig. 2 is a bottom view of the same. Fig. 3 is a vertical longitudinal section on line $x-x$, Fig. 1, taken through one cylinder; Fig. 4, a vertical transverse section on line $y-y$, Fig. 3; Fig. 5, a vertical longitudinal section through the second cylinder, taken on line $z-z$, Fig. 1; and Fig. 6 a vertical transverse section on line $c-c$, Fig. 1.

Similar letters of reference indicate corresponding parts.

The inclosing casing or body of my improved steam and gas meter is formed of two parallel hollow cylinders, $A A'$, of equal size, which are closed by heads A^2 , secured thereto, said cylinders being cast in one piece and provided with a valve-chest, A^3 , at the upper part, that extends transversely across both

cylinders and carries above the same the casing for the usual counter employed in piston-meters of this class.

The valve-chest A^3 is provided with the usual inlet-port, a , for the gas or steam, the gas or steam passing from said chamber through the valve-passages of the pistons $B B'$ to the double T-shaped bottom part, A^4 , of the cylinders $A A'$, said bottom part being provided with a central outlet-port, b^x , as shown in Fig. 6. The pistons $B B'$ partake of the character of slide-valves, and are made of cylindrical shape and fitted closely to the interior of their respective cylinders. Both pistons are provided at their upper parts with narrow inlet-openings $b b'$, which communicate with diverging channels or passages $d d'$, which are of the same shape in each piston.

Above the inlet openings $b b'$ of the pistons $B B'$ are arranged gridiron slide-valves $C C'$, which are curved so as to fit to the rounded surface of the pistons. The openings $f f'$ of the slide-valves $C C'$ register with the inlet-openings $b b'$ of the pistons. Each gridiron slide-valve is provided at the ends with studs g , which abut against the end walls of the valve-chest A^3 , when the piston arrives at the end of its stroke, so as to cause the slide-valve to shift, closing thereby one set of openings and opening the other set.

The parts so far described are the same as the corresponding parts shown in my prior patent heretofore referred to.

The bottom A^4 of each cylinder $A A'$ is arranged with short vertical holes or passages $i i$, which connect, respectively, with the ends of the cylinders $A A'$, the channels $d d'$ of the pistons and a cup-shaped channel, d^2 , located at the bottom of each plunger intermediately between the channels $d d'$. The cup-shaped channel d^2 establishes the connection with the short vertical passages $i i$ at the bottom of one cylinder and with those of the adjoining cylinder, so that the alternate working of the pistons is produced.

Below the bottom A^4 are arranged pipes $D D' D^2 D^3$, which are provided with short offsets, that are fitted tightly to the smooth under side of the bottom A^4 by fastening devices $E E'$. The pipes $D D' D^2 D^3$ cross each other diagonally in the manner shown in dotted lines in Fig. 1 and in full lines in Fig. 2, and

are secured to the bottom A⁴ by bails E' and binding-screws E², two of the bails being provided at one end with studs n that press on the pipes D D', which are located closer to the bottom A⁴, as shown clearly in Fig. 5, while the remaining bails are applied directly to the pipes D² D³ and D D'. The binding-screws E² are passed through holes of the bails and retained thereon by screw-nuts n', as shown in Figs. 3 and 5.

The cross-pipes D D' D² D³ and vertical passages i i have the advantage that they can be readily cleaned, so as to get all the core-sand and dust out of the same, which is impossible when the cross-passages are cast in the bottom of the casing. If this core-sand and dust is not removed it will get into the cylinders and prevent the meter from operating properly, as the low pressure of the natural gas would not overcome the resistance exerted by the sand on the pistons. Another disadvantage is that the core-sand will score the interior surface of the cylinders and destroy the tight fit of the pistons.

At the upper part of the cylinders A A' are formed rails m, parallel with the side walls of the valve-chest, which rails serve as guides for the gridiron slide-valves C C'. The pistons B B' are provided with screws o, which pass through short slots o' of the slide-valves, the screws preventing the pistons from turning axially in the cylinders. The screws o are provided with enlarged heads, between which and the valves are arranged helical springs o², which produce a gentle pressure on the slide-valves, so as to prevent them from jumping out of place when the pistons are running at considerable speed. The screw o of one of the pistons is connected by an upwardly-extending stud, o³, with the recessed end of the counter-lever L, so as to operate the same, as shown in Figs. 3 and 6, by which the connection of the piston and registering-counter is made.

The operation of my improved steam and gas meter is the same as the operation of the meter described in my prior patent referred to.

The advantages of my improved meter are that the pistons of the same have an easy and steady motion, so as to respond quickly and effectively, even to a low pressure exerted

thereon; that the same can be cleaned easier from time to time by detaching the bottom cross-pipes; that it can be manufactured cheaper, as all the cross-passages are constructed of pipes and fastening devices, which can be made at less expense than when the cross-passages are cast into the bottom, which requires an expensive casting.

Having thus described my invention, I claim as new, and desire to secure by Letters Patent—

1. The combination of an inclosing-casing having a chest at the upper part and a bottom with short vertical passages, reciprocatory pistons having channels forming slide-valves, slide-valves resting on said pistons, detachable cross-pipes connecting the vertical passages in the bottom of the casing, and fastening devices for attaching said cross-pipes to the bottom of the casing, substantially as set forth. 65

2. The combination of an inclosing-casing having a chest at the upper part and a bottom with vertical channels, reciprocating pistons having channels forming slide-valves, grid-iron slide-valves resting on said pistons, diagonal cross-pipes connecting the bottom-passages of the casing, bails for retaining said cross-pipes, and binding-screw posts for attaching the bails and pipes to the bottom of 70 the casing, substantially as set forth. 75

3. The combination of an inclosing-casing having cylinders and longitudinal guide-rails, reciprocatory pistons, curved gridiron slide-valves resting on said pistons, and screws attached to the pistons and passing through slots at the slide-valves, substantially as set forth. 85

4. The combination of an inclosing-casing having cylinders and guide-rails, reciprocatory pistons, gridiron slide-valves resting on said pistons, screws connecting the pistons with the slide-valves, and helical springs interposed between the heads of the screws and slide-valves, substantially as set forth. 90

In testimony that I claim the foregoing as my invention I have signed my name in presence of two subscribing witness.

A. C. CHRISTENSEN.
